United States Patent Office.

GEORGE D. GOODRICH, OF JOLIET, ILLINOIS.

Letters Patent No. 61,732, dated February 5, 1867.

IMPROVEMENT IN CLAY-PIPE MACHINES.

The Schedule referred to in these Letters Patent and making part of the same.

TO ALL WHOM IT MAY CONCERN:

Be it known that I, GEORGE D. GOODRICH, of the city of Joliet, in the county of Will, and State of Illinois, have invented certain new and useful Improvements in Machinery for the Manufacture of Clay Pipes; and I do hereby declare that the following is a full, clear, and exact description thereof, reference being had to the accompanying drawings of two sheets, forming a part of this specification, in which—

Figure 1 is a side view with a portion of one of the posts removed.

Figure 2, a cross-section of the standard D, showing the upper rests.

Figure 3, an enlarged view of a portion of the standard D, next to and above the upper part of the frame.

Figure 4, a top view of the head sliding in the shaft D.

Figure 5, a side view of the same.

Figure 6, a front view of the same.

Sheet 2, Figure 7, a top view of the head of the standard or post E.

Figure 8, a side view of the same.

Figure 9, a side view of the device for lowering the empty troughs.

Figure 10, a top view of the bottom of the same.

Figure 11, an end view of the trough.

Figure 12, a side view of the carrying frame.

Figure 13, a top view of the same.

Figure 14, a top view of the windlass for elevating the trough, showing the manner of stopping it.

Figure 15, a side view of the wheel to which the support of the cutting wires is attached.

Figure 16, a side view of the outer end, the sliding shaft; and

Figure 17, a top view of the sliding shaft and section of the wheel shown in fig. 15.

Like letters refer to the same parts in all of the figures.

The nature and object of my invention consist in constructing a series of machinery to be used in the manufacture of clay pipes for drain tile, sewer pipes, &c., so that the operation will be continuous from the time the clay is forced through the mould until the same trough is returned to receive a section of pipe, and the pipe cut into proper lengths or sections from a mould through which the pipe is passed continuously; in providing such machinery with an improved platform for receiving the pipe from the mould into the receiving trough; in providing a wheel to operate the sliding-shaft and cutter; in providing a sliding-bar below such platform with stops to regulate and adjust the lengths of the section of pipe; in providing such wheel and sliding-bar with cams and spring; in providing the wheel with arms extending beyond and the entire length of the receiving platform to which the cutting wires are attached; in constructing and providing an elevator at the side of the receiving platform, and operating at the side of a single post or standard to receive and elevate the trough and pipe; in the peculiar arrangement and construction of such elevator; in providing such post or elevator with an automatic stop and rest; in the peculiar construction of such rest; in providing the operating shaft with a cylinder operated by a lever-spring catch and conical or wedge-shaped retractor; in providing such machinery with a post or standard, having guides on the side to guide the dumping platform; in providing dumping platforms, one of which will operate the other; in the peculiar construction of such dumping platform; in providing a platform to receive the empty troughs from such dumping apparatus, and in the several combinations hereinafter set forth and claimed as new.

To enable other skilled in the art to make and use my invention and my improved machinery, I will proceed to describe its construction and operation.

It is designed to use this machinery in a two-story building, in which event A¹ will represent the first floor, and A² the second, and the posts of the frame A will represent the walls or supports of the building. In a one-story building the frame A will be made in any convenient manner. The mould is not represented, but the pipe is discharged from the mould through the standard or post, B, on to the sliding support, C, which will slide upon the arms j' so as to occupy a portion of the space between the post B and the trough O. I attach a post, H, to the floor, opposite the post B, at a suitable distance therefrom; and at a proper distance above the floor to give the arms of the cutter a free movement I insert a bar or shaft, J. To this shaft I attach the wheel I and collar b, of the cutter and the lower arms or timbers of the carrying device. These arms, L, are provided on each side with screws, a a, upon which the cross-bars m and m' rest, and by means of which the height of the frame is adjusted to adapt it to the size of the pipe passing into the trough O. To these cross-bars m and m' I attach wheels or rollers, T, which extend beyond the bar m, and are provided with flanges at each end to keep the movable platform N', (more fully shown at fig. 13,) in position. Cross-timbers or bars, H', supporting the cross-wheels or rollers, u, are placed upon the bars m. The rollers u are also provided with flanges, and project

slightly above the movable platform N' . Upon these cross-rollers the trough O is placed, as shown. To the shaft I attach a sliding-bar, K , at the upper side this shaft at the outer end it may be attached to C by i , or left, as shown; and near this passes under the collar b of the cutter; at the other end the arms or stops d are attached. These arms d project upwards sufficiently to stop the friction of the pipe from carrying the trough O over the frame, and the shaft is secured in place by passing under the rim of the circular band, l' , of the wheel I , (figs. 15 and 17.) To the sides of this bar J I attach a spring, g , (fig. 17.) which is provided with a hook, h , which operates on a catch, i , which is attached to the sliding-bar K , and is unhooked by the cams k of the plate l' of the wheel I . To the wheel I are attached arms, $e e$, at opposite sides, which are extended far enough to allow the bent portion to pass entirely around the receiving frame or device, and are long enough to pass beyond said frame. To the bent portion of these arms I attach small wires, ff , at their outer ends, and at the inner ends they are attached to the wheel I and the collar b in any convenient manner. These wires are placed so as to come very near the ends of the trough O , and by giving the wheel I a half revolution, cut the continuous pipe into proper lengths or sections, when it is ready to be removed and elevated to the upper floor. For the purpose of elevating it I attach to the side of the standard or post D , which has a T-shaped groove or guide, Z' , which guides the head P of the elevator. This head (figs. 4, 5, and 6,) is made of sufficient length to keep it steady and prevent bending on the guide, and on each side is a projection, which has an upper and lower cam, o and n , and to its front is attached a plate, m , which is provided with arms, ll , that are carried out and bent to receive the ends of the trough O . At the upper end of the head P there is an eye or loop attached, into which the cord, g , is fastened; a similar one is made at the lower end to attach a weight if necessary. At a proper distance above the second floor or top of the frame, bent arms, W , (figs. 1, 2, and 3,) are hinged to the sides of the post D , so as to stand over the bent arms ll . The ends of these arms are extended through the post D into the guide cavity Z' , so as to be operated by the cams n and o at the sides of the elevator head P . They are also provided with springs, z , to throw them under the trough O as soon as it has been elevated to the required height. These springs, in the form of attachment shown, at their outer ends rest against pendent projections attached to the bent arms, but may be applied directly to the back of the arms, or in any convenient manner, the design being to make the arms work automatically, so that the attendant will not need to be always at this point. To complete the automatic working I attach to a driving-shaft, Q , a small head, x , permanently, and a cylinder, R , loosely. This cylinder is slid upon the shaft by means of the lever w , and when brought against the head x it is held by friction or proper clutches, and secured by the spring u , which is provided with a stop, y , (figs. 1 and 14,) that rests against the upper end of the lever w . A cord, g , is attached to this cylinder and passes up over a sleeve or pulley on the top of the post S , and over to a similar one at the top of the post D , and down to the head P of the elevator. To this cord I attach a conical block, t , which is attached to the cord at such a distance from the spring u as that when the elevator passes the bent arms w , this block will press the spring and release it from the lever w , so that the cylinder R will cease revolving with the shaft, and the elevator commence descending. The upper end of the lever w is made wide enough for the stop y of the spring u to rest against it in order to prevent the conical block from catching in its ascent. The empty troughs are lowered by means of the apparatus attached to the shaft E , shown at figs. 1, 7, 8, 9, and 10. This standard or post is provided on opposite sides with T-shaped grooves or guides, Z , similar to that in post D . The top of this post is provided with cross-bars, $i' i'$, which support the friction-rollers $g' g'$, over which passes the cord a' , which supports at each end a dumping frame, only one of which is shown, but both are made alike, and a description of one will apply to both. The head h' is fitted to the interior of the guide groove Z , and has a projection at its front to which the upper end of the arm Y is hinged. This arm is also bent, and is of sufficient length to pass over and to the bottom of a trough, where its lower end is hinged to a projection, c' , of the bottom X . The bottom X has eyes or loops at each end, and lateral projections, m' , at the inside, which are fitted to the sides of the post E . A bail, b' , bent in the form shown in figs. 1 and 9, is attached at the eyes e' to the bottom, and at the upper end to the cord a' . This cord a' passes over and around the rollers or pulley g' and under the friction clutch d' , (fig. 8,) and is provided with a swelled or double conical block, f' , which operates the friction clutch d' , which is also double acting. The object of this is to check the motion of the dumping frame in its descent, so that the empty troughs will not be precipitated upon the platform F with too much force and injure the troughs. When the bottom X passes below the end of the post E , it swings under the end of said post, when it will turn upon the bail b' and dump the trough; the block f' should therefore be so located that it will strike the friction clutch just before the bottom X passes below the end of the post, and being double acting only one will be required for both frames, but if desired it can be duplicated and placed on both sides. A dumping platform F , provided with rollers v , is placed below the end of the standard or post E , to receive the empty troughs as they descend. The rollers v are placed on the same plane as the upper rollers u of the receiving frame. This platform is supported in position by any convenient method. The sizes of the several posts of my machinery will be governed by the length of the sections of clay pipe to be made, and by the material used in its construction, as it can nearly all be made of wood, or may be economically made principally of iron. Ordinary sections of pipe weigh from forty to about one hundred and twenty pounds in the trough, so that a strength of parts which will sustain a weight of two hundred pounds will be sufficient.

The operation is as follows: The ground or prepared clay is forced at 1 from the mould through the post B into the sliding rest c which slides on its arms j' , about half way from the post to the trough, and should be located about one-eighth of one inch higher than the trough O ; it then passes into and through the trough, which is prevented from sliding or rolling back by the stops a , which are held and locked by the springs g . When the pipe has passed through the trough the attendant then takes hold of the arm e and gives the wheel I a half revolution, which motion causes the wires f to pass through the pipe and cut it at both ends, and also releases the spring catch $g h$ by means of the cams k and the stops d , when the trough is rolled back till the circular

cavities n' are directly over the rollers u , which lets the trough down on to the platform N which rests upon the rollers T , when it is pushed with N down to the post D , which brings the trough over the arms l . The cylinder R is then thrown into gear and it is taken up on the elevator; platform N is immediately returned to its position, another trough taken from platform F and rolled to the same place which the other occupied. When the head P of the elevator reaches the points k' of the arms w , the cams o , pressing against the back of the points k' , open the arms and allow the trough to pass through, and the springs z will return them as soon as the trough passes them, or the points k' pass the lower end of P ; and to ensure their perfect working, the cams n at the lower end of the head block P strike against the front of the points k' and force them under sufficiently by its weight in descending. As soon as the head block is past the points k' , the block t on the cord strikes the spring u and releases the cylinder R , when the elevator will descend, leaving the trough on the spring arms w ; this is necessary, as it would require an additional attendant if this part did not work automatically. The trough is then taken and emptied, when it is thrown on to the platform X , where its weight causes it to descend. The peculiar construction and method of hanging this platform causes it to keep nearly horizontal until it passes the bottom of the post, when it will cant and slide the trough off into platform F , when it is ready to be used again, and the friction clutch d' with the conical block f' will break the force of the descent so that it will be landed without injury. I use five of the troughs O in operating the machinery, and when complete will be found very useful in the manufacture of clay pipes, where the pipe is made continuous and in a horizontal position.

Having thus fully described my improved machinery, I will now point out those parts and combinations which are new.

What I claim as my invention, and desire to secure by Letters Patent, is—

1. The wheels or rollers T , cross-rollers u , and platform N N' , in combination with the trough O , substantially as and for the purposes specified.
2. The wheel I , when provided with the arms e , and cams k , substantially as and for the purposes specified.
3. The sliding-bar K , provided with the arms or stops d .
4. The spring g , provided with the hook h , in combination with the catch i , and cams k of the wheel I , constructed and operating with the shaft J , and sliding-bar K , substantially as specified.
5. The bent arms e , and cutting wires f , arranged and operating substantially as set forth.
6. The head P of the side elevator, when provided with the cams o and n upon each side.
7. The head P , constructed substantially as described in combination with the bent arms l .
8. The bent arms w , when provided with the points or projections k' .
9. The arms w in combination with the springs z , projections k' , and head P of the elevator, arranged and operating substantially as and for the purposes specified.
10. The combination and arrangement of the side elevator, constructed substantially as set forth, with the guide post D , and automatically operating arms and rest w .
11. The conical or wedge-shaped block t , when attached to an elevating cord, rope, or chain, substantially as and for the purposes specified.
12. The spring u , provided with the ledge or catch y , in combination with the lever w , having its head or upper end enlarged, substantially as and for the purposes specified.
13. The combination and arrangement of the cylinder R , lever u , spring u , rope q , and block t , with the elevator P , and automatic rest w , constructed and arranged substantially as and for the purposes specified.
14. The standard or post E , provided with the T-shaped guides Z , substantially as specified.
15. The double wedge or conical block f' , when attached to the cord a' , for the purposes specified.
16. The double-acting friction clutch d' , arranged and operating substantially as specified.
17. The combination and arrangement of the rollers g' and clutch d , with the cord a' , and double-acting block f' .
18. The dumping platform X , when provided with a hinge c , on one side, and guides m' on the other, substantially as specified.
19. The platform X in combination with the bent bar Y , and sliding head h' , constructed and hinged substantially as specified.
20. The bent bail b' , when so bent as to pass the back of the platform X , and hinge or attach to it near the front at e , substantially as and for the purposes specified.
21. The combination and arrangement of the platform X , hinged bent bar Y , sliding head h' , with the bail b' , cord a' , and standard E , substantially as and for the purposes specified.
22. The combination and arrangement of two dumping platforms, constructed substantially as specified, with a single guide standard, so that one will elevate the other and bring its opposite one into position while dumping a trough.
23. The receiving platform F , provided with rollers v , located on the same plane as the rollers u of the receiving frame, substantially as specified.
24. The screws a a , for adjusting the height of the receiving frame to the different sizes of pipe being made.
25. The use or employment of rollers or carriers for supporting and carrying a trough used to receive and carry off clay pipes which are forced from the die continuously and cut while in motion.
26. The arrangement of the cutting wires in combination with a receiving trough, so that both ends of the section of pipe will be cut; and the wires while cutting take the same motion as the pipe and trough, and produce a square cut across a continuous pipe while in motion.

GEORGE D. GOODRICH.
